UNITED STATES PATENT OFFICE.

GEORGE C. PLUMMER, OF CHICAGO, ILLINOIS, ASSIGNOR TO THOMAS J. HRUBY, OF CHICAGO, ILLINOIS.

BUCKLE.

No. 866,217.

Specification of Letters Patent.

Patented Sept. 17, 1907.

Application filed April 3, 1907. Serial No. 366,082.

To all whom it may concern:

Be it known that I, GEORGE C. PLUMMER, a citizen of the United States, residing at Chicago, in the county of Cook and State of Illinois, have invented a new and 5 useful Improvement in Buckles, of which the following is a specification.

My invention relates more particularly to improvements in strap-buckles of the variety employing a relatively stationary frame-member and a sliding member 10 coöperating therewith and carrying the gripping means for releasably fastening the free end of the strap to the buckle.

The object of my invention is to improve upon buckles of this type as hitherto constructed, to the end of 15 simplifying and cheapening the construction and at the same time adapting the buckle to hold with equal firmness, straps of different sizes.

Referring to the accompanying drawing; Figure 1 is a perspective view of a strap equipped with a buckle 20 embodying my invention; Fig. 2, an enlarged section taken at the line 2 on Fig. 1 and viewed in the direction of the arrow; Fig. 3, a rear face view of the buckle illustrated in Fig. 1.

My improved buckle comprises a front or main frame 25 6 preferably of the rectangular and curved shape represented, and composed of end-sections 7 and 8, an intermediate section or cross-bar 9, and side-sections 10; and a rear frame 11 slidably confined on said main frame and coöperating therewith for the purpose hereinafter 30 explained. The rear frame 11, which is shorter than the frame 6, comprises end-sections 12 and 13, side sections 14 and an intermediate section or cross-bar 15 provided with teeth 16, extending toward the bar 12 and inclinedly into the opening provided between the section 35 8 and cross-bar 9. Ears 17, provided on the side sections 10 are bent to overlap the side-sections of the rear frame and form guides for holding the front and rear frames flatwise together.

On the back of the rear frame 11 is a flange 18 preferentially formed by bending in a direction away from the teeth 16, the metal cut away to form the opening between the teeth and the section 12, to form a flange substantially in the form of a half circle in cross-section. This flange affords a rounded bearing for the purpose 45 hereinafter stated.

The buckle is attached to a strap, such as that shown at 19, by looping one end thereof about the cross-bar 9 of the front frame and end-section 13 of the rear frame and then securing it to the adjacent portion of the strap, 50 as by a rivet 20. By thus securing the strap to the buckle the bar 9 and section 13 are confined within the

strap-loop so formed, thereby preventing the two frames from separating and at the same time permitting the frames to be moved one upon the other. With the strap in position to be fastened, its free end may be 55 releasably secured in the buckle by introducing it from the rear thereof through the registering openings in the frames provided between the end-section 12 and cross-bar 15, and the end-section 8 and cross-bar 9, respectively, and then, if desired, inserting it through the 60 loop adjacent to the section 7 thereby causing the teeth to engage the strap. The free end of the strap thus fastened to the buckle is caused to bear against the flange 18 with the effect of sliding the rear frame on the front frame and consequently causing the teeth to firmly grip 65 the strap. The rounded bearing 18 tends to reduce wear on the strap to the minimum. Moreover, this flange affords a great leverage for moving the rear frame which permits of the buckle being made of sufficient dimensions to enable it to be used with straps of greatly 70 varying thicknesses.

It will be noted that by constructing the buckle in a manner to permit of the two frames being held against separation, by the fixed end of the strap engaging both frames, and by providing guides for the purpose described, the buckle-parts may be stamped from sheet-metal and readily assembled without requiring an undue amount of labor, since the parts are adapted to be stamped out in the form in which they are finally assembled. 80

What I claim as new and desire to secure by Letters Patent is:

A buckle comprising, in combination, a front frame consisting of end-sections and an intermediate section secured together, a rear frame movable on said front frame and comprising end-sections and an intermediate section secured together, gripping teeth on said rear-frame intermediate section extending into the space between said front frame intermediate section and one of its end-sections, guides formed on the sides of said front frame and overlapping the sides of said rear frame to maintain the frames flatwise together, and a flange of a form approximating a half circle in cross section on the end-section of said rear frame adjacent to said teeth, formed of the metal cut away to form the space between said last-named end-section and the teeth, said frames being constructed and arranged to permit one end of a strap to be looped over the intermediate section of the front frame and the adjacent end-section of the rear-frame and the other end of the strap to be inserted between said teeth 100 and the adjacent end-sections of the front and rear frames. 95

GEORGE C. PLUMMER.
